SPOOL

George G. Tucker, Jr., Berwyn, Ill., assignor to
Hubbard Spool Company, Chicago, Ill., a corporation of Illinois

Application December 15, 1949, Serial No. 133,147

4 Claims. (Cl. 242—123)

1

The present invention relates to a spool construction, and in particular to a spool construction having a strengthened head member. The spools of the present invention find use for holding metallic stock, such as wire, or textile stock, such as cord, thread, yarn, tape or the like.

Although material such as rayon or nylon thread is comparatively light, when the same is wound upon a spool it builds up a substantial axial thrust against the spool heads, tending to move the heads axially away from the ends of the cylindrical barrel or hub of the spool. Therefore, it is necessary to provide the head assemblies with adequate strength to resist substantial axial stress occasioned by such winding or unwinding. This increase in strength should not be accompanied with a substantial increase in the weight of the spool, since it is desirable for shipping and operating purposes to keep the weight of the spool as low as possible.

With the foregoing in mind, an object of the present invention is to provide a lightweight, reinforced spool construction.

Another object of the present invention is to provide a spool construction having reinforced head portions which have the ability to adequately withstand the axial thrust presented to the spool head during winding of the medium on the spool.

Still another object of the present invention is to provide a spool construction in which the hub portion and head portions of the spool are interlocked to substantially stiffen and strengthen the head portions without materially increasing the weight of the spool assembly.

Other and further objects and features of the present invention will be apparent to those skilled in the art from the following description of the attached sheets of drawings in which:

Figure 1 is an end elevational view of a spool constructed according to the present invention, with a portion thereof broken away to illustrate the means by which the hub portion is joined to the head portion;

Figure 2 is a broken vertical sectional view taken along the line II—II of Figure 1 with parts in elevation;

Figure 3 is a fragmentary end elevational view of a modified form of spool produced according to the present invention;

Figure 4 is a fragmentary sectional view taken along the line IV—IV of Figure 3;

Figure 5 is a fragmentary end elevational view of still another modification of the spool assembly constructed in accordance with the present invention; and

2

Figure 6 is a fragmentary cross-sectional view taken along the line VI—VI of Figure 5.

As shown on the drawings:

Reference numeral 10 denotes generally a cylindrical hub portion forming the body of the completed spool, and having a plurality of tabs 11 extending from both ends thereof for securing the hub 10 to the remainder of the spool structure, as will be hereinafter described.

The hub portion 10 may conveniently be formed of a seamless cylinder of metal or as shown in Figures 1 and 2, the hub may consist of two semi-cylindrical sheet metal stampings which are joined together by a pair of strips 12 welded or otherwise secured to the semi-cylindrical members across the joints to form a continuous hub structure.

The head portion of the spool assembly consists of an annular head portion 13 having an inwardly turned, outer peripheral edge portion 14, said head portion 13 is provided with slots 13a through which the tabs 11 extend. The projecting tabs are then turned back against the outer surface of the head portion 13. Said head portion 13 is likewise secured along its inner edge 13b to a tubular insert 15.

The joints between contacting metal surfaces in the spool assembly are preferably all formed by brazing, and a convenient means for accomplishing this consists of painting the surfaces of the prefabricated members with a brazing compound at the point where the juncture is to be made, assembling the various pieces in their correct alignment, and placing the completed assembly in a furnace at a temperature sufficiently high to braze the contacting surfaces together by the fusion of the brazing compound.

For the purpose of providing a more rigid structure for the head assembly, a corrugated or embossed end plate 16 is provided. In the embodiment shown in Figures 1 and 2, the end plate 16 is provided with a flanged portion 17 at its outer peripheral edge in nesting engagement with the inwardly turned lip portion 14 of the head assembly and is brazed thereto.

The end plate 16 is also provided with a series of inwardly depressed portions 18 and 19 bottomed against corresponding surfaces of the head member 13, and secured thereto.

The innermost edge of the end plate 16 is turned inwardly, as indicated at 30, and secured at this point to the tubular insert 15.

One of the features of the present invention consists in providing a series of spaced depressions 20 arranged about a circle in the end plate 16, the depressions 20 being of such a depth that

each depression seats against a turned back tab portion 11 of the hub 10. Here again, the base of each depression 20 is suitably brazed to a tab 11.

The structure shown in Figures 1 and 2 thus forms a reinforced head structure for the spool assembly. The hub 10, the head member 13, the end plate 16, and the tubular insert 15 are all integrally united into a rigid structure. Any thrust tending to urge the head assembly away from the hub is thus resisted by both the head member 13 and the end plate 16 acting together as a unit. The axial thrust is equally distributed throughout the head structure by virtue of the unions between the tabs 11 and both the end plate 16 and the head member 13. The added strength given to the hub structure by means of this arrangement does not materially increase the weight to the spool assembly so that its inertia likewise is not materially increased.

A different type of end plate structure for securing the head member 13 to the hub 10 is shown in Figures 3-4. As shown in these figures, an end plate 21 is provided with a series of depressions in a stepped arrangement such that the radially outer depression in each series is offset to a greater extent than the adjacent inner depression. Each of the inner depressions 22 formed in the end plate 21 is of sufficient depth to be snugly seated against the outwardly turned tab 11 of the hub 10. This tab 11, of course, is secured as by means of brazing to both the base of the depression 22 and the abutting surface of the head member 13. Radially outwardly of each depression 22, there is provided a second depression 23 which is formed in the end plate 21 of sufficient depth to be bottomed against the outer surface of the head member 13. Thus, each tab 11 is confined between the bottom of a depressed portion 22 and the end plate 21, and beyond each tab 11, corresponding depressed portion 23 is bottomed against the end plate 21 thereby locking each tab 11 in place. Otherwise, the details of the structure shown in Figures 3 and 4 are identical with corresponding parts shown in Figures 1-2.

Still another embodiment of the present invention is illustrated in Figures 5-6. In the modification shown in those figures, an end plate 24 is formed with a relatively wide depression 25 bottomed against a corresponding surface of the head member 13. The tabs 11 extend through suitable slots 13a and 24a in the head member 13 and the end plate 24, respectively, and are then turned over into contact with the outer surface of the depression 25.

Each of the modifications shown in the above description is substantially more rigid and capable of resisting axial thrust to a greater degree than any of the spools now in common use. The fabrication of the spool assembly shown herein is relatively inexpensive since only stamped sheet metal is employed in its construction. By the particular construction shown, a substantial amount of reinforcement is afforded to the head structure of spool assemblies without materially increasing the weight.

While only one head structure has been illustrated for purposes of convenience, it will be understood that the structure of the opposite head is identical with that shown. Thus, a thrust load in an axial direction due to the pressure

of the medium being wound will be resisted by both head assemblies. Further, a force supplied against one head assembly tending to force it off the hub will, due to the interaction of the tab against the corresponding head therein, tend to force the opposite head assembly against the adjacent end of the hub. Thus, in effect, axial pressure outwardly on one head assembly tends to hold the other assembly against axial outward movement.

It will be understood that modifications and variations may be effected without departing from the scope of the novel concepts of the present invention.

I claim as my invention:

1. A spool comprising a tubular hub, a head member of circular configuration at each end of said hub, an end plate on each of said head members having spaced offset surfaces thereof bottomed on the adjacent head member, said end plate also having a series of depressions formed therein, and a plurality of tabs at each end of said hub, each tab having one surface thereof joined to one of said head members and the opposite surface thereof joined to the base of one of the depressions in said end plate.

2. A spool comprising a tubular hub, a head member of circular configuration at each end of said hub, an end plate on each of said head members having a plurality of depressions extending radially outwardly but terminating short of the outer peripheries of said head members, a plurality of tabs on each end of said hub extending through said head members and secured in position between a head member and the bases of said depressions.

3. A spool comprising a tubular hub, a head member of annular configuration at each end of said hub, an end plate secured at its peripheral edge to an edge of one of said head members and having a plurality of offset portions, some of said offset portions being bottomed on and secured to said head member, and a plurality of tabs at each end of said hub portion extending through said head members and secured in position on said head members beneath the remaining offset portions.

4. A spool comprising a tubular hub, an annular head member at each end of said hub, an end plate secured at its outer peripheral edge to an edge of one of said head members, and having offset portions terminating short of said head member, and other offset portions immediately adjacent said first named portions secured to surfaces of said head member, and a plurality of tabs on said hub portion extending through said head member and secured in position between said head member and the base of said first named offset portions.

GEORGE G. TUCKER, JR.
